BY

The image shows a rectangular frame with diagonal hatching on the left side. Inside the frame, there is a signature in cursive ink that reads "Joseph J. Root, Jr." Below this, another line of text reads "Gifford, Scull & Bangs" followed by "ATTORNEYS" in a smaller font.

UNITED STATES PATENT OFFICE

2,140,334

TOOL FOR APPLYING DUST GUARD CAPS
TO JOURNAL BOXESJoseph J. Root, Jr., Chicago, Ill., assignor to Union
Tank Car Company, Chicago, Ill., a corporation
of New Jersey

Application December 31, 1936, Serial No. 118,515

1 Claim. (Cl. 81—15)

This invention relates to a novel and improved form of tool for applying dust guard caps to journal boxes, the novel features of which will be best understood from the following description and the annexed drawings, in which I have shown a selected embodiment of the invention and in which:

Fig. 1 is a plan view of a dust guard cap with which the tool is to be used;

10 Fig. 2 is an elevation of the dust guard cap appearing in Fig. 1;

Fig. 3 is a view, partly in section and partly in elevation, showing how one end of the dust guard cap is bent;

15 Fig. 4 is a view, partly in elevation and partly in section, showing how the tool is applied to a journal box, this view being taken approximately on the line 4—4 of Fig. 6;

Fig. 5 is a view of part of the same structure
20 as appears in Fig. 4 and showing the tool after it has completed its operation;

Fig. 6 is a view approximately on the line 6—6
25 of Fig. 4;

Fig. 7 is a view approximately on the line 7—7
of Fig. 5.

Various forms of dust guard caps have been devised to prevent the entry of dust into the dust guard chamber of journal boxes, and such dust guard caps have been more or less successful. Some of the more recent forms which have been adopted are in the form of sheet metal strips with flanged sides which have their ends bent over the opposite edges of a journal box, but caps of this form oftentimes worked loose and became lost because they were not clamped on with sufficient tightness. Moreover, they require two men to apply them, usually with a hammer. To overcome these difficulties, I have devised the tool forming the subject matter of this application, by which a more satisfactory job can be done by a single workman.

In the accompanying drawings I have shown a portion of a conventional truck frame 1, such as is commonly used on railroad cars, and which includes a journal box 2 which may likewise be of any usual or desired form. This journal box receives and is supported by the journal 3 of a wheel 4, the usual bearings for the journal being omitted, as they are not necessary for an understanding of my invention.

The journal box may be supplied with the usual pivoted lid 5 at the outer end thereof, and at the opposite end it may be provided with the usual dust guard chamber 6 in which a dust

posed. The top of this chamber is closed by a dust guard cap 8, and the tool covered by this application is used in applying this cap securely in place so as to tightly close the top of the chamber 6.

As best shown in Figs. 1 and 2, the cap is formed of sheet metal having depending flanges 9 adapted to engage opposite walls of the dust guard chamber, and is also provided at its opposite ends with lips 10 and 11 which, for the sake of convenience, I shall refer to hereinafter as the opposite ends of the cap.

Before this cap is placed upon the journal box, the end 10 thereof is bent to the proper form to engage an edge of the journal box, which may be done by the use of a suitable forming tool 12, as shown in Fig. 3. The cap is then put in place on top of the dust guard chamber, with the bent end 10 in engagement with the adjacent edge 13 of the journal box and with the other end 11 overlapping the opposite edge 14 of the journal box, as plainly shown in Fig. 4. It will be seen that this end 11 is formed so that it overhangs the edge 14 and is inclined downwardly at a decided angle.

I then place on top of the cap a tool formed according to my invention and which comprises a body 15 formed of spaced bars 16 having between them at one end a hook 17 which may be detachably held in place by pins 18 passing through aligned holes 19 in the bars and hook. In order to adjust the hook 17 lengthwise of the body, I provide a series of such holes so that, upon removal of the pins, the hook may be moved lengthwise of the body and relocated with respect thereto.

At the opposite end of the body, I pivotally support a second hook 20 as by a pin 21 passing through aligned holes in the bars and in the hook which is placed between the bars. Intermediate the two hooks, I pivotally support a brace 22 having a head 23 which is adapted to engage the inner surface of the flange 24 of the car wheel which supports the journal box. The brace preferably has a threaded engagement 25 with the head so that the head may be adjusted lengthwise of the brace to engage flanges at different distances from the tool. The hook 20 is so shaped as to engage the end 11 of the cap and bend it into tight engagement with the adjacent edge 14 of the journal box, and, in order to move the hook into and out of engagement with the bent end 11, I place on the hook a handle 26, as shown, which clears the flange 24.

I believe that the operation of the tool will

be plain from the above description, but it may be summarized briefly as follows:

First the cap is bent at one end 10, as indicated in Fig. 3, after which the cap is placed in position as shown in Figs. 4 and 6. Then the tool is placed in position with the body contacting with the cap and with the relatively fixed hook 17 in engagement with the end 10 which has been previously bent to closely fit the adjacent edge 13 of the journal box. The head 23 is then brought into engagement with the inner surface of the flange 24 on the wheel 4, and finally the handle 26 is moved downwardly so that the hook 20 will bend the end 11 of the cap tightly into engagement with the adjacent edge 14 of the journal box. The spacing of the hooks 17 and 20 is such that the two ends 10 and 11 will clamp the dust guard cap securely and tightly to the journal box. There are several standard sizes of journal box, and enough holes 19 may be provided so that the distance between the hooks may be varied and thus the two may be used with any standard construction. The arrangement of the holes and pins is a convenient form of adjustment to use when dealing with a few predetermined standards, although, of course, it will be understood that other forms of adjustment may be used where found desirable, without departing from the scope of my invention. During the de-

pression of the handle 26, the brace 22 will prevent the cap and tool from moving upwardly and will thus aid materially in providing a tight engagement of the cap and journal box.

While I have shown the invention as embodied in a specific form, it is to be understood that various changes in details may be made without departing from the scope of the invention as defined by the appended claim.

I claim:

A tool for applying a sheet metal dust guard cap to a journal box supported by a flanged wheel, said tool comprising a body having a surface adapted to contact with said cap and having a fixed hook at one end adapted to engage a bent end of the cap and hold it against an edge of said box, a brace secured to the body and having a head adapted to engage the interior of said flange to force said surface of the body against the cap and thus force the cap against the box, and a second hook pivoted to said body adjacent the other end thereof and movable towards and away from said box, the distances between said fixed hook and said pivot and the distance between said pivot and said pivoted hook being such that when said pivoted hook is moved toward said box it may bend the other end of said cap against another edge of the box.

JOSEPH J. ROOT, JR.
